CLAIM

The ornamental design for a set of shoe panels, as shown and described.

DESCRIPTION

FIG. 1 is a right side elevation view of a set of shoe panels showing my new design mounted on a shoe shown in broken lines;

FIG. 2 is another right side elevation view thereof, with the panels shown separate from the shoe;

FIG. 3 is a rear elevation view thereof;

FIG. 4 is a front elevation view thereof;

FIG. 5 is a top plan view thereof; and,

FIG. 6 is a bottom plan view thereof.

The broken lines shown in the drawings represent portions of shoe in FIG. 1 that form no part of the claimed design. All surfaces not shown form no part of the claimed design.
